UNITED STATES PATENT OFFICE.

CHARLES H. WRIGHT, OF BROOKLINE, MASSACHUSETTS.

PROTECTED CHECK.

Application filed September 9, 1924. Serial No. 736,721.

To all whom it may concern:

Be it known that I, CHARLES H. WRIGHT, a citizen of the United States, residing at Brookline, in the county of Norfolk and State of Massachusetts, have invented certain new and useful Improvements in Protected Checks; and I do hereby declare the following to be a full, clear, and exact description of the invention, such as will enable others skilled in the art to which it appertains to make and use the same.

The present invention relates to bank checks, travelers' checks, letters of credit, stock certificates, cash fare receipts, and similar instruments, and is more particularly intended to limit the amount payable on such instruments.

Various methods have been devised to prevent altering or raising the amount payable on a bank check. The best known methods in actual practice consist in printing or engraving the instrument upon a specially treated paper, which visibly indicates erasure or alteration of writing or printing, and actually embossing the check paper with the amount to be paid through the employment of a special stamping or embossing machine. Although one or both of these methods are quite generally employed in connection with written instruments of this character, more particularly bank checks, nevertheless it is possible for one skilled in the art to successfully vary or alter the check without detection. Furthermore the second of the two methods above-described requires a special machine which must be adjusted and used in connection with the protection of each instrument. Another method heretofore attempted but not so generally used is to provide a protective margin for the check forming an integral part thereof and having limiting amounts written or printed thereon, which are arranged in a manner to indicate desired limits when the check is separated from the stub. This form of protection is generally unsatisfactory, however, due to the fact that with any of the suggested arrangements of limiting amounts the space required for the protective margin and the spread between the limiting amounts are both so great as to render the method impractical. Furthermore the time and skill required to properly tear off certain of these protective margins makes them impractical for use in cases

where considerable numbers of checks are being written and handled. The very material variation in size of the checks and the irregularity of outline due to these protective margins also militates against their use, as it interferes wth the handling of the checks in the bank.

The object of the present invention is to provide an improved form of check or similar instrument having a protective margin which occupies a minimum of space, which may be readily torn off, and which limits the the check closely to the amount written or printed in the body.

With this and other objects in view, the various features of the invention consist in certain novel features of construction, combinations and arrangements of parts, hereinafter described and claimed, the advantages of which will be obvious to those skilled in the art from the following description.

In the accompanying drawings illustrating the preferred form of the invention, Fig. 1 represents the face of a bank check having the improved form of protective margin interposed between the check and the stub; Fig. 2 is a view similar to Fig. 1 illustrating the check filled in and separated from the stub along the proper line of tear-off to limit the check at the margin; Figs. 3 and 4 illustrate a slightly modified form of protective margin embodying the improved features of the form of margin illustrated in Figs. 1 and 2, Fig. 3 showing the check before detachment and Fig. 4 showing the check after being filled in and separated from the stub and Fig. 5 is a plan view on a reduced scale of a conventional paper cutter employed for severing the check from the stub.

The preferred form of the invention is illustrated in connection with a bank check of conventional form. In this embodiment of the invention, the body of the check is indicated generally at 10 and is provided with the name of the bank on which it is drawn, the date, and spaces for the payee and the amount for which the check is issued. In addition, the face of the check is provided with a clause indicating that the amount written in the body of the check shall not exceed the largest amount printed in the marginal guard. Interposed between the body of the check and the usual stub

12 is a marginal protective guard 14 which occupies a minimum of space and is designed to protect amounts up to \$10,000 with limits of less than \$10. In the illustrated embodiment of the invention, the limiting amounts are arranged in a series of units or blocks corresponding to tens, hundreds and thousands, respectively. Each of these units or blocks includes numerals from 10 to 90 or 10 from 1 to 9 in arithmetical progression to protect amounts ranging from \$10 to \$9,990. The arrangement of successive units of the individual amounts in each block and the blocks themselves is such that the body of 15 the check may be readily detached from the stub on the desired line of tear-off with little or no difficulty. This is accomplished by arranging each series of numbers constituting a single unit diagonally with respect to the marginal guard, the sums being 20 printed either as numbers or as words corresponding to such numbers. The separate blocks or units are arranged vertically or parallel to the margin of the check, providing a comparatively narrow guard of 25 uniform width from end to end. In the illustrated embodiment of the invention, the separate units, that is blocks of numerals indicating tens, hundreds and thousands, 30 are enclosed in parallelograms superimposed one above the other and having the adjacent marginal edges in alignment to facilitate tear-off. The background of the guard surrounding the blocks is tinted in a characteristic manner to emphasize and set off 35 the units. The shape of the blocks and their location with respect to one another is such that any desired amount may be indicated on the marginal guard with a zigzag line 40 consisting of a series of straight lines of varying length joined by a series of predetermined obtuse angles. As indicated clearly in Figs. 1 and 2, a check for \$7,640 is protected by severing the check between 45 the numerals 7 and 8 on the thousand block, between the numerals 6 and 7 on the block of hundreds, and between the numerals 40 and 50 on the block of tens. It will be 50 evident to those skilled in the art that this form of marginal guard imparts a substantially predetermined and regular contour to the marginal edge of the check, irrespective of the amount to be protected. The 55 tear-off of the marginal guard may be accomplished through the use of a metal cutter having two straight cutting edges disposed at an angle corresponding to the angularity of the blocks or units, the successive positioning of the cutter at proper points with 60 relation to the blocks permitting the check to be detached on a zigzag line. As shown in the drawings, the block of tens is indicated at 20, the block of hundreds at 22 superimposed thereabove, and the block of 65 thousands at 24. The designation of the in-

dividual blocks is conveniently shown at the bottom of each block, that is the lowermost block 20 is provided with the designation "dollars" as indicated at 26, the middle block with the designation "hundred" as 70 indicated at 28, and the uppermost block with the designation "thousand" as indicated at 30. In order to further protect against alteration, the words corresponding to different numerals in cases where they do not occupy the entire width of the block 75 are flanked by stars 32 or other suitable characters, which tend to prevent erasure of a word and substitution of a word designating a higher numeral. 80

It will be evident from the foregoing that the essential feature of the present invention relates to a plurality of series of numerals or words designating numerals, each series consisting of numerals or words corresponding thereto aligned diagonally with respect to the marginal guard and written or printed on parallel lines extending diagonally to the guard and to the alignment of the numerals, all of the numerals being written on parallel lines and each series being offset with respect to the next adjacent series. It will be furthermore obvious that although the illustrated embodiment of the invention indicates a marginal guard provided with three units of numerals, the invention contemplates the employment of either more or less units as desired, although it is believed that the arrangement shown in the drawings covers the vast majority of checks and similar instruments. 100

In the form of marginal guard shown in Figs. 3 and 4, the series of units or blocks indicated generally at 40 are inclined in a direction opposite to that shown in Figs. 1 and 2 and the individual numerals in each block read from top to bottom rather than from the bottom upwardly, as shown in Figs. 1 and 2. In this form of guard, the tear-off is similar to that shown in Figs. 1 and 2, although the inclination of the numerals and the location of the individual blocks offer certain definite advantages in connection with the tear-off. In removing the check from the stub, a cutter 50, such as shown in Fig. 5, having an obtuse angle corresponding to the angle between the sides and top and bottom of the blocks is employed. One edge of the cutter is aligned with the side of the block and the cooperating edge is located between the numerals along the desired line of tear-off. Starting at the top of the check shown in Fig. 3, one edge of the cutter is placed in alignment with the left hand margin of the thousand block and the cooperating edge extends on a line below the numeral 7. The length of this edge corresponds to the width of the block. Upon completion of the tear-off through the thousand block, the cutter is 115

next positioned with one edge in alignment with the left hand margin of the hundred block and the cooperating edge beneath the numeral 6, the tear-off being completed 5 through the width of the hundred block. This operation is then repeated through the block of tens, completing the tear-off of the check. By proceeding in this manner, the check may be readily detached along the 10 desired line of tear-off and there is no liability of destroying the marginal guard, due to the fact that all of the blocks except that being removed are completely exposed to the view of the operator.

15 It will be evident to those skilled in the art that if the body of the check, cash receipt, or similar instrument is written in an even amount, one or more entire blocks or units may be entirely detached from the 20 marginal guard, leaving a portion of one only of the units connected with the instrument. An important advantage inherent in the present method of protecting checks is due to the fact that the largest amount is 25 indicated not only upon the marginal guard of the check but also upon the stub from which the check has been detached. The stub indicates instantly the amounts for which checks have been drawn and prevents 30 any substantial error in checking the amounts.

It will be further evident to those skilled in the art that although the illustrated embodiment of the present invention indicates 35 a protective guard written in dollars and fractions thereof, nevertheless the present invention may be equally well embodied for protecting checks or similar instruments written in other currencies.

40 The term "numeral" has been adopted throughout the claims to designate the series of ordinate numerals whether printed as numbers or as words corresponding to numbers and wherever such a term is used 45 throughout the claims it is to be understood that it covers the numerals printed or written in any one of several characteristic forms.

I claim—

50 1. A form for checks or like instruments having a marginal guard provided with a plurality of sets of ordinate numerals arranged on diagonal parallel lines, the marginal alignment of each set of numerals being parallel with the adjacent set and inclined to the margin of the instrument to cause the guard to be separated upon a series 55 of diagonal lines.

60 2. A form for checks or like instruments having a marginal guard provided with a series of ordinate numerals arranged on parallel diagonal lines, the marginal alignment of each set of numerals being inclined to the margin of the instrument and making 65 an obtuse angle with the lines of numerals

whereby the guard is detached along a series of straight diagonal lines joined by obtuse angles.

3. A form for checks or like instruments having a comparatively narrow marginal 70 guard containing a plurality of blocks of ordinate numerals arranged in parallel diagonal lines, the left hand margin of each block of numerals being inclined to the margin of the guard and making an obtuse 75 angle with the alignment of the numerals.

4. A form for checks or like instruments having a marginal guard provided with a series of sets of ordinate numerals, each set forming substantially a parallelogram inclined to the margin, the several sets being arranged lengthwise of the margin and substantially contacting with one another in a manner to permit the guard to be detached 80 throughout its length by a zigzag line passing through all of the sets of numerals.

5. A form for checks or like instruments having a marginal guard of uniform width throughout its length provided with a plurality of sets of ordinate numerals extending 90 throughout the length of the guard and written on parallel lines inclined to the margin of the guard, the marginal alignment of each set of numerals making an obtuse 95 angle with the lines of numerals.

6. A form for checks or like instruments having a marginal guard of uniform width provided with a series of parallelograms each containing a set of ordinate numerals, the numerals being written on lines inclined to the 100 guard, and the margins of each parallelogram being in alignment with the opposite margins of the next adjacent parallelogram whereby the guard may be detached 105 on a continuous zigzag line.

7. A form for checks or like instruments having a marginal guard at the left hand end provided with a series of sets of ordinate numerals written on parallel diagonal lines and extending lengthwise of the guard, the left hand margin of each set of numerals being parallel to the same margin of the next adjacent set and making an obtuse angle with the alignment of the numerals.

8. A form for checks or like instruments having a marginal guard of uniform width, a series of parallelograms located within the guard and arranged diagonally with respect thereto, the background of the guard being ornamented to set off the parallelograms, and a set of ordinate numerals arranged within each parallelogram, the numerals being written on diagonal inclined 110 lines.

9. A form for checks or like instruments having a marginal guard provided with a series of sets of ordinate numerals written on parallel diagonal lines, each set of numerals reading downwardly from 1 to 9, 115 120 125 130

and the marginal alignment of each set of numerals making an obtuse angle with the lines of the numerals.

10. A form for checks or like instruments having a marginal guard provided with a series of blocks of ordinate numerals, the blocks indicating progressively higher units and extending from the bottom of the guard

upwardly, and the numerals being written on parallel diagonal lines, making an obtuse angle with the marginal alignment of the blocks. 10

In testimony whereof I have signed my name to this specification.

CHARLES H. WRIGHT.
